A. HADLEY

EXPANSIBLE BRACELET

Filed Feb. 9, 1925

Inventor

Art Hadley
By Joseph Miller
Attorney

UNITED STATES PATENT OFFICE.

ART HADLEY, OF PROVIDENCE, RHODE ISLAND, ASSIGNOR TO THE HADLEY COMPANY, OF PROVIDENCE, RHODE ISLAND.

EXPANSIBLE BRACELET.

Application filed February 9, 1925. Serial No. 8,027.

To all whom it may concern:

Be it known that I, ART HADLEY, a citizen of the United States, residing at Providence, in the county of Providence and State of 5 Rhode Island, have invented new and useful Improvements in Expansible Bracelets, of which the following is a specification.

This invention relates to certain new and useful improvements in expansible bracelets, and the primary object of the invention 10 is to provide a bracelet which enables the links to be easily and quickly connected and disconnected, and at the same time to be prevented from being accidentally disengaged, 15 in normal use.

The invention further aims to provide means of the type described which is of simple and economical construction, involving a minimum of parts compactly assembled.

20 In the drawings:—

Figure 1 is a longitudinal sectional view of a fragment of a bracelet constructed in accordance with the present invention;

25 Figure 2 is a section on line 2—2 of Fig. 1;

Figure 3 is a section on line 3—3 of Fig. 1, and

Figure 4 is a detail perspective view of one of the slides.

30 In proceeding in accordance with the present invention each link consists of a box 1 and a slide 2. Each slide has a right-angular inner end 3 engaged with one end of a coil spring 4, the opposite end of which latter abuts the front end of the box. The outer 35 ends 5 of the slides are bent into hoopshape and slidably project through openings 6 provided therefor in the front ends of the boxes. The rear of the links are slotted to form bars 7 for engagement with the hooks 5. The 40 bottoms of the boxes are formed with transverse slots 8 for receiving the finger nail or any sharp instrument capable of being projected through the slot to engage the right-angular ends 3 of the slides to hold the latter in outer position thereby to dispose the hooks at a distance from the front ends of the boxes to facilitate connection and disconnection of the slides from the boxes.

45 In operation, in order to connect adjacent links, the hook of the slide of one box is moved outwardly and held by engaging same

with a finger nail or instrument inserted in slot 8, whereupon the boxes are moved to occupy relatively right angular positions, whereupon the hook is engaged with the bar 55 7 of the adjacent box and the boxes then moved to lie in the same plane.

To disconnect, the reverse operation is followed, namely, the adjacent links are distended, and the slide of one held in outward 60 position, whereupon, the links are disposed at right angles and the hook of the slide then moved out of engagement with the bar 7.

Having thus described my invention, what 65 I claim as new and desire to secure by Letters Patent is:—

1. In an expansible bracelet, boxes having top, bottom and side walls, each box having a transverse slot extending across 70 its bottom, and having a slot at one end and a bar extending across its opposite end, a longitudinally movable slide in each box having a right angular end and a hook-shaped end the latter projecting 75 through the slot at the box end and being engaged with the bar of an adjacent box, and a coil spring in the box engaged with the right angular end of the slide and with the end of the box having the slot, the slots 80 in the box bottoms being of a size to admit a means of engaging the right-angular end of the slide to hold the latter against longitudinal movement and with the hook thereof projected outwardly of the box. 85

2. In an expansible bracelet boxes having top, bottom and side walls, each box having a transverse slot extending across its bottom, a longitudinally movable spring pressed 90 slide in each box having a hook-shaped end the latter projecting outwardly beyond an end of the box, and means on the opposite end of the box to engage the hook of the slide of an adjacent box, the slots in the box bottoms being of a size to admit a means of 95 engaging the slide thereof to hold the latter against longitudinal movement and with the hook thereof projected outwardly of the box.

In testimony whereof I have signed my name to this specification.

ART HADLEY.
